United States Patent

Des. 235,393
Patented June 17, 1975

235,393

DISPLAY STAND

Roland E. Loomis, Menlo Park, Calif., assignor to House
of Health, Inc., Santa Clara, Calif.

Filed July 12, 1973, Ser. No. 378,784

Term of patent 14 years

Int. Cl. D20—02

U.S. Cl. D6—24

FIG. 1 is a perspective view of a display stand showing my design;

FIG. 2 is a side elevation view of the design of FIG. 1, it being understood that the side not illustrated is the same as the illustrated side;

FIG. 3 is a front elevation view of the design of FIG. 1, it being understood that the back of the design is the same as the front; and

FIG. 4 is a top plan view of the design of FIG. 1.

I claim:

The ornamental design for a display stand, as shown and described.
